B. F. GRANT

IRONING BOARD

Filed May 1, 1923

BY

R. U. Smith

ATTORNEY.

INVENTOR.
Benjamin F. Grant

UNITED STATES PATENT OFFICE.

BENJAMIN F. GRANT, OF LOS ANGELES, CALIFORNIA.

IRONING BOARD.

Application filed May 1, 1923. Serial No. 635,841.

To all whom it may concern:

Be it known that I, BENJAMIN F. GRANT, a citizen of the United States, residing at Los Angeles, county of Los Angeles, State 5 of California, have invented new and useful Improvements in Ironing Boards, of which the following is a specification.

This invention is an ironing board, breakfast table, or the like, adapted to be folded back in vertical position when not in use, and adapted to be readily swung outwardly and fixed in horizontal position when it is desired to use the same.

It is the object of the invention to provide a folding board which may be conveniently vertically adjusted and held at the desired height for use; and to provide an extremely simple and inexpensive construction wherein a supporting brace is pivoted 20 to the board, and a releasable locking connection is provided between the board and said brace, the members being vertically adjustable and having means for engaging one of the same at any desired height so as 25 to prevent vertical displacement thereof.

The invention will be readily understood from the following description of the accompanying drawings, in which:

Fig. 1 is a vertical section showing the 30 board in position for use.

Fig. 2 is a similar view showing the board folded to closed position.

Fig. 3 is a section on the line 3—3 of 35 Fig. 1.

Fig. 4 is a section on the line 4—4 of Fig. 2.

Fig. 5 is a detail vertical section of the 40 locking connection between the board and its brace.

Fig. 6 is a view similar to Fig. 1 showing a modified form of the invention.

Fig. 7 is a section on the line 7—7 of 45 Fig. 6.

The improved folding board is illustrated as mounted in a casing 1 having a rear wall 2 and an open front. Vertical grooves or guideways 3 are formed in the side walls of the casing, and at the upper portion of the casing the side walls between said grooves 50 and the front of said casing preferably project into the latter as shown at 4, in order to form beads against which the closure means for the casing is adapted to abut. At the lower portion of the casing, the side walls in front of grooves 3 are flush with the rear

portions of said side walls as shown in Fig. 4.

The folding board is shown at 5, and is of a width adapted to be received in the casing between projections 4, the inner end 60 of the board having dowel pins 6 projecting beyond either side thereof, with said pins vertically and pivotally movable in grooves 3.

A brace 7 is provided for the board, and 65 is of a width adapted to fit within the lower portion of the casing, so that when said brace is swung to vertical position as shown in Fig. 2, the upper end thereof will abut against beads 4 to properly position the 70 brace as a door for the lower portion of the open front of the casing. A door 8 hinged to the side of the casing is adapted to close the upper portion of the open front 75 of the same.

A cross bar 9 is mounted on the inner side of brace 7 in slightly spaced relation above the lower end thereof, said bar terminating in dowel pins 10 projecting beyond the sides of the brace and adapted to be received in grooves 3 for vertical and swinging adjustment of said brace.

The upper end of the brace is pivoted to the underside of board 5 by a hinge 11 positioned at the inner edge of the end of the brace, said end of the brace being angularly disposed as shown at 12, so that when the parts are in position for use as shown in Fig. 1, the board 5 will abut against end 12 beyond said hinge, in order to limit relative swinging movement between said brace and board in one direction.

A releasable locking connection is provided between the board and brace to prevent relative swinging movement between 95 said members in the opposite direction when the parts are in operative position. As an instance of this arrangement, a spring catch 13 may be mounted on the underside of board 5, in position to engage a cooperating 100 fastening means 14 at the outer side of brace 7, when the board is in horizontal position.

The catch is readily manually released by pressing upon its end 13', when it is desired 105 to swing the board and its brace upwardly and back into folded position as shown in Fig. 2.

A vertical ratchet 15 is mounted in the casing upon the rear wall 2 thereof, said 110

ratchet being at a height to aline with the lower end of brace 7 when the latter is in operative position, and a spring pawl 16 on said brace is adapted to engage any one of the ratchet teeth for holding said brace in vertically adjusted position.

By the construction as thus described it will be seen that the board 5 will be held at any desired height in its horizontally disposed operative position, the dowel pins 6 in grooves 3 preventing horizontal displacement of the board, and the fixed connection between the board and its brace, together with the supporting of the lower end of the brace by ratchet 15, preventing downward swinging of said board. The fixed connection between the board and brace in conjunction with the engagement of dowel pins 10 in grooves 3, will, in similar manner hold 20 the board against upward tilt.

In order to adjust the height of the board, it is simply necessary to lift the same to the desired point, the fixed connection between the brace and board elevating the former as the board is lifted, with yielding spring pawl 16 riding over the ratchet 15 until the board is again released, when said pawl will reengage the ratchet. When the height of the board is to be lowered, the brace 7 remains fixed relative to the board, and the outer end of the latter is tilted upwardly the slight distance permitted by play of dowel pins 10 and 6 in grooves 3. The brace 7 is thus shifted sufficiently to disengage pawl 16 from its ratchet, so that the board and brace may be vertically lowered to the desired height, after which the outer end of the board is released so that the board and brace may tilt downwardly the distance permitted by the play of the dowel pins in the grooves, in order to again engage the pawl with the ratchet.

When the board and brace are swung to folded position, the lower end of the latter is adapted to be shifted forwardly in casing 1 for closing the front of the same as previously described. For this purpose grooves 3 are provided with vertically spaced forwardly extending enlargements 20 and 21 near the lower ends of the same, the parts being so arranged that when the device is in folded position, dowel pins 10 will be received in enlargements 21 to permit shifting of the brace, and dowel pins 6 will enter enlargements 20 so that board 5 may be correspondingly shifted in order to remain parallel to its brace.

In the modification of the invention illustrated in Fig. 6, instead of the brace 7' being held against vertical displacement when the parts are in position for use, the inner end of board 5 is adapted to be engaged at vertically spaced points in order to hold the board in vertically adjusted position.

As an instance of this arrangement, the

lower end of brace 7' is angularly disposed as shown at 25, in order to abut against rear wall 2 of the casing when the parts are in operative position, and forwardly and downwardly curved notches 26 are formed 70 in grooves 3 at vertically spaced points along the upper portions of said grooves.

Dowel pins 6 are adapted to enter notches 26 so as to prevent vertical displacement of the board, the fixed connection between 75 the board and brace together with the abutment of said brace against the rear wall of the casing, retaining the board in horizontal position as previously described.

The board may be vertically adjusted by 80 disengaging dowel pins 6 from the notches and sliding said dowel pins in grooves 3 until the board is at the desired height, and then reengaging the dowel pins in the adjacent set of notches 26. In order to fold 85 the board, the fastening connection between the board and brace is released, and the dowel pins 6 are disengaged from notches 26, to permit upward swing of the board and brace, and downward movement of the 90 lower ends of said members, until the parts are in folded position as previously set forth.

In Fig. 6 I have also shown a modified form of fastening connection between the 95 board and its brace. For this construction the end of brace 7 is forked as shown at 7' and is pivoted at the inner edge of its end to the underside of board 5, by hinge 11, with the angular end 12 of the brace 100 adapted to abut against the board 5.

A locking rod 35 is pivoted at 36 in the forked end of the brace, the lower end of said rod forming an operating handle, and the upper end of said rod having an end 105 surface 37 adapted to engage the underside of board 5 in rear of hinge 11, when the board is in horizontal position.

The board and brace will thus be held against relative swinging movement toward 110 one another, so that the brace may be fixed relative to the board as previously described, and by swinging end 37 of the locking rod forwardly, the board and brace will be disengaged, so that they may be folded into 115 inoperative position.

I claim:

1. A device of the character described comprising a support, a board and a brace each having a vertically movable pivotal 120 connection with said support, a pivotal connection between said brace and board at the underside of the board and near one end of the brace, said end of the brace forming an abutment surface bearing against the underside of the board when in operative position, and a releasable connection between said brace and board for locking said members against relative swinging movement in the 125 opposite direction. 130

2. A device of the character described comprising a support, a board having a vertically movable pivotal connection with said support, a brace pivoted at one end to said board, a pawl upon the opposite end of said brace, a vertical ratchet on said support adapted to be engaged by said pawl when the board is in horizontal position, and means for releasably locking said board and brace members against swinging movement relative to one another.

3. A device of the character described comprising a casing having guideways in the sides thereof spaced inwardly an appreciable distance from the front of said casing, a board having pivot pins received in said guideways for vertical and swinging adjustment of said board, a brace for said board having pivot pins received in said guideways for vertical and swinging adjustment of said brace, said guideways having forwardly extending enlargements at the lower ends thereof adapted to receive the pivot pins of said brace when the board and brace are swung into vertical position to permit forward movement of said brace so as to lie flush with the front of the casing and close the same, a releasable connection between said board and brace for locking said members against swinging movement rela-

tive to one another when the board is in horizontal position, and vertically spaced means in said casing adapted to releasably engage one of said members when the board is in horizontal position so as to hold said members against vertical displacement. 35

4. A device of the character described comprising a support, a board having a vertically movably pivotal connection with said support, a brace for said board, a pivotal connection between said brace and board at the underside of the board and near one end of the brace, said end of the brace forming an abutment surface bearing against the underside of the board when in operative 40 position, a releasable connection between the brace and board for locking said members against relative swinging movement in the opposite direction, the end of the brace remote from said pivotal connection being 45 adapted to abut against the support when the board is in horizontal position, and vertically spaced means on the support adapted to releasably engage one of the said members to hold the same against vertical displacement. 50 55

In testimony whereof I have signed my name to this specification.

BENJAMIN F. GRANT.
